ORIFICE GUARD CONSTRUCTION FOR
DISPENSERS

George H. Packwood, Jr., St. Louis, Mo.

Application August 25, 1947, Serial No. 770,426

2 Claims. (Cl. 222—501)

1

The present invention relates to a dispenser for powdered soap, or the like. In the description to follow, it will be described in connection with the dispensing of powdered soap, although it will be understood that it can be used with other finely divided materials.

It is an object of this invention to provide a dispenser of this character, wherein there is an outlet at the bottom of a bowl, which outlet is controlled by a valve, and wherein there are means that prevent the collection of soap particles around the outlet and on the valve because of the wetting of such parts. More particularly, it is an object of this invention to provide a dispenser having a valve and orifice opening so designed that the splashing of water onto these parts and the consequent adhesion of soap thereto are largely prevented. Also, it is an object to provide a dispenser having a splash guard that will prevent water splashed onto, or collecting on the outside of the dispenser, from draining onto the valve.

A further object of the invention is to provide a dispenser of this type wherein the valve and operating parts can be removed through the bottom opening of the dispenser. A further object is to provide a dispenser as aforesaid wherein there is a particularly desirable adjustment mechanism.

A particular object of the invention is to provide a dispenser of this kind wherein there is a bowl with an outlet opening at the bottom, a valve controlling flow through the opening, which valve is operated in such wise that the hand of the user may come close to the bottom opening, but with means to prevent the splashing of water onto the parts, and consequent adhesion of soap thereto.

In the drawings:

Fig. 1 is a front elevation of the dispenser;

Fig. 2 is a diametrical section through the dispenser, taken from side-to-side of Fig. 1;

Fig. 3 is a side elevation of the dispenser partly broken away to show elements in section; and

Fig. 4 is a view similar to Fig. 2 showing a modified operating means.

The dispenser comprises an outer bowl or container 10 that has tapering inwardly converging lower walls 11 and a cover 12. The cover is removable and is designed to be controlled by fittings (not detailed) that may be operated by a key.

The bowl has an orifice 15 in its bottom. Above the orifice and spaced therefrom is an inner cone or false bottom member 16 that converges down-

2

wardly and has an opening 17 therein that is smaller than the main orifice 15.

Across the upper part of the bowl 10, there is a strap 18 that is secured by upturned ends bolted to the top of the bowl as at 19. These bolts have heads cooperable with slots in the top, for attachment of the top. One end of this strap likewise receives a plate 20 that is employed to hold locking means for holding the cover 12 in place.

This strap has a center opening 21, through which the upper end of a relatively massive plunger 22 projects. There is a removable pin, such as a cotter key 24, above the strap 18 and passing through the plunger 22 to suspend the plunger on the strap 18.

This plunger 22 extends downwardly through the opening 17 of the cone 16 to the orifice 15, whereat it receives and supports a valve disc 23. This valve disc is shaped approximately to the diameter and shape of the main orifice 15, but it can slide therethrough. It is adapted to close the orifice 15 sufficiently to prevent the flow of soap therethrough, and sufficiently to prevent the ingress of water from the bottom of the dispenser into the bowl. However, the valve 23 is removable downwardly through the orifice.

In Fig. 2, the valve is operated by a handle 25 that passes through an opening 26 in the side of the bowl and has a reduced pin-like extension 27 on its inner end. This pin portion passes through a transverse opening 28 in the plunger 22, and has a removable pivot pin 29 in the form of a cotter pin that engages it rockably with the plunger. The handle 25, as is evident, can fulcrum on the wall of the bowl and thereby cause the plunger 22 to be elevated, raising the valve 23.

Over the strap 18, there is a shield 30 that is U-shaped in cross section, as shown in Fig. 3, and which may be engaged over the strap. One end of this U-shaped shield is arcuate, as shown in Fig. 2 at 31, so that the strip may be inserted at its other end over the strap and rocked down into position. In position, it extends down to a point somewhat below the handle 25.

Mounted also on the strap, there is a closure member 33 that is held to the strap removably by screws 34. This closure forms, with the strap, an enclosing means to receive the upper end of the plunger and to contain an adjustment stop 35 in the form of a screw that is threaded into the top of the closure 33 and is provided with a lock nut 36. This screw 35 is axially aligned with the plunger 22 and is designed to limit adjustably the upward stroke of the plunger. As the screw

stop 35, the closure 33, the strap 18 and the bowl 26 are all rigidly fastened together, the upward impact of the relatively heavy plunger 22 against the screw on the upstroke of the valve will agitate the bowl for the purpose of breaking up any packing of the soap within the dispenser, as will be described. In like manner, the free fall of the plunger into closing position agitates the bowl when the pin 24 strikes the strap element 18.

The valve 23 is shown as being concave upwardly on its inner portion, but flared downwardly at 40 on its rim. This valve is designed to be suspended approximately at the bottom of the inwardly converging portion of the bottom 11 of the dispenser. It closes the orifice 15 at the smallest part of the converging walls 11. The valve is attached to the plunger by a headed pin 41 that fits into an axial opening in the bottom of the plunger, and is held there by pressed fit. If desired, a cross pin or the like may be employed.

This dispenser is provided with a flaring bottom ring-like element 42 that may be formed as a separate piece from the bowl 10, but can be formed integrally therewith. It will be noticed that the member 42 flares outwardly and downwardly below the orifice 15 and carries the main dispenser wall below and outwardly of the valve. When made as a separate element, the guard ring 42 is stepped outwardly from the bottom of the orifice portion of the bowl.

The dispenser of Fig. 4 is the same as that in Fig. 2 except that, instead of having the handle at the side of the dispenser, it is formed as a continuation 50 of the plunger. In this case, the handle has a pin-like projection 51, that may be of the same size as the pin-like projection 27 of the handle 25, which projects upwardly into the opening in the bottom of the plunger. Reference to Fig. 2 will show that the pin-like projection 51 is identical with the stem portion of the headed element 41 that holds the valve 23 in place, and that there is a similar cross pin. Thus, an identical plunger 22 for both handle constructions may be used, eliminating the necessity of manufacturing separate parts for this. Where the handle 50 is employed in place of the handle 25, the shield 30 may be eliminated as its function is not required.

The operation of the dispenser is as follows:

The cover 12 may be removed and a suitable quantity of powdered soap or other finely divided material to be dispensed filled into the bowl 10. Where the handle 25 is employed, the shield 30 will prevent the building up of the soap level around the handle, and thereby prevent the interference by such soap with the operation of the handle. Soap has the characteristic of tending to pack, and of being hygroscopic, so that it adheres to the parts and packs against them when it can do so. It may, therefore, interfere with operating parts that are immersed in it. The purpose of the shield is to prevent the rising of any substantial quantity of soap around the handle and its connections.

The upper end of the plunger, in any case, rises into the closure 33, which forms, with the strap, a completely enclosed space to receive the adjustment parts and stop for the upstroke, as well as the key that limits the downstroke of the plunger. Consequently, soap cannot get into these parts.

The soap charged into the bowl 10 descends through the opening 17 and rests upon the upper surface of the valve 23. When this valve is closed,

there can be no discharge of soap through the opening. If the handle 25 or the handle 50 is operated to elevate the plunger, the valve is lifted so that it rises above the orifice 15, which is to say that it rises beyond that portion of the bottom of the dispenser that is of substantially the same diameter as the outer diameter of the valve. It passes into the outwardly and upwardly converging bottom portion 11, so that soap flowing around the edge of the valve may fall through the orifice 15 and descend into a hand disposed below the orifice.

In this elevation of the valve, the soap that has descended through the opening 17 to rest upon it is elevated against the false bottom 17. This causes such soap to be ejected over the edge of the valve. This preferred construction is obtained by providing a relationship between the upper surface of the valve and the side of the orifice 17, so that the soap descending through the orifice will spread outwardly in a conical pile on top of the inner upwardly concave portion of the valve and come to rest without spreading outwardly against the walls of the bowl portion 11. The angle of repose of the powdered soap being known, the foregoing can be accomplished by relating the size of the orifice 17 and the size of the valve to this angle of repose. The upwardly concave shape of the valve 23 increases the angle of repose relative to the horizontal. The valve 23 can be made flat but the upwardly concave shape is preferred.

As the plunger is raised, which is normally an action that takes place with relatively little movement of the handle, the plunger strikes the screw 35 and, as previously mentioned, causes agitation of the contents, so that any lumping or cohesion of the soap particles is broken up, and consequently the soap will then descend through the opening 17 upon the release of the handle and return of the valve to its former position. Such agitation is repeated upon release of the handle and descent of the valve. This insures a charge of soap for each operation of the handle.

With two-handed operation as indicated in Fig. 2, where one hand is used to operate the handle 25 and the other hand is held below the orifice to receive the soap descending therethrough, the guard 42 prevents the hand from being brought against the valve parts or against the orifice adjacent thereto. Consequently, if the hand is wet, water is prevented from getting to these parts. The outward flare on the guard member 42, and the outwardly stepped arrangement of the guard, provide a construction wherein the vertically descending soap normally does not strike against the inner surface of the guard walls, at least at their lower parts. If water is splashed or otherwise put on the guard by the hand, it is thereby located away from the parts of the guard against which descending soap may strike. This is an important feature in preventing the collection of soap adhering to the valve and the bottom parts of the dispenser. The guard extends down low enough that the hand cannot normally swell upwardly when pressed against it far enough to contact the valve parts. Furthermore, any water splashed onto, or otherwise collecting on the outside of the bowl, descends on the outside of the guard and is conducted to below and outwardly from the valve.

The construction is such that the substitution of the handle 50 for the handle 25 is readily accomplished with a minimum number of parts, owing to the identity of shape of the tongue portion of

the pin 41 and the tongue portion 51 on the handle 50.

It may thus be seen that a dispenser has been provided which obtains a sure operation, with agitation of the parts, with complete adjustability, with the prevention of the collection of soap on the bottom of the dispenser, and with ready serviceability. Also, service is facilitated as removal of the closure 33 permits the keys 24 and 28 to be withdrawn, and the valve and plunger withdrawn through the orifice.

What is claimed is:

1. In a dispenser for powdered soap material and the like, a bowl having bottom walls downwardly converging to an outlet orifice and flaring smoothly outwardly in an extension below the orifice, the orifice constituting the narrowest section of the walls, a valve in the bowl extending at least substantially to said walls at the orifice for closing the orifice, means to support the valve in said closing position, means to move the valve away from said orifice to permit descent of material through the orifice, the extension projecting below the orifice far enough to prevent the hand of the user from contacting the valve when such hand is engaged against the bottom of the extension.

2. In a dispenser for powdered soap material and the like, a bowl having bottom walls down-

wardly converging to an outlet orifice and flaring smoothly outwardly in an extension below the orifice, the orifice constituting the narrowest section of the walls, the valve in the bowl extending at least substantially to said walls at the orifice for closing the orifice, means to support the valve in said closing position, means to elevate the valve above said orifice to permit descent of material around the valve and through the orifice, the extension projecting below the orifice far enough to prevent the hand of the user from contacting the valve when such hand is engaged against the bottom of the extension, said means to elevate the valve comprising a handle secured to the valve and projecting downwardly therefrom through the extension and below the same.
